(57) **CLAIM**

The ornamental design for a support frame with parabolic side beams, as shown and described.

DESCRIPTION

FIG. 1 is a perspective view of support frame with parabolic side beams showing our new design;

FIG. 2 is a top view thereof;

FIG. 3 is a front view thereof;

FIG. 4 is a rear side view thereof;

FIG. 5 is a perspective view thereof;

FIG. 6 is a bottom side view thereof;

FIG. 7 is a right side view thereof; and,

FIG. 8 is a left side view thereof.
